US0D1069126S

(12) **United States Design Patent** (10) **Patent No.:** **US D1,069,126 S**
(45) **Date of Patent:** **** Apr. 1, 2025**

(54) **INSTRUMENT TOWER**

(71) Applicant: **Auris Health, Inc.**, Santa Clara, CA (US)
(72) Inventors: **Jonathan Mendoza**, San Francisco, CA (US); **Frankie Vazquez**, San Francisco, CA (US); **Toby A. Stopper**, San Francisco, CA (US); **Quinn Slater Huffstetler**, San Francisco, CA (US); **Wonbin Choi**, San Francisco, CA (US)

(73) Assignee: **Auris Health, Inc.**, Santa Clara, CA (US)

(**) Term: **15 Years**

(21) Appl. No.: **29/909,181**

(22) Filed: **Aug. 2, 2023**

Related U.S. Application Data

(60) Continuation of application No. 29/797,871, filed on Jul. 2, 2021, now Pat. No. Des. 994,890, which is a division of application No. 29/634,007, filed on Jan. 17, 2018, now Pat. No. Des. 924,410.

CLAIM

The ornamental design for an instrument tower, as shown and described.

DESCRIPTION

FIG. 1 is a top, front, left perspective view of an instrument tower;

FIG. 2 is a front view of the instrument tower;

FIG. 3 is a rear view of the instrument tower;

FIG. 4 is a left-side elevation view of the instrument tower;

FIG. 5 is a right-side elevation view of the instrument tower;

FIG. 6 is a top plan view of the instrument tower; and,

FIG. 7 is a bottom plan view of the instrument tower.

In the drawings, the broken lines are for the purpose of illustrating portions of the instrument tower, that form no part of the claimed design.

1 Claim, 6 Drawing Sheets
